WINDING DRUM FOR WALL DRIERS

Original Filed July 8, 1927

Louis Judelson

INVENTOR

BY *Arthur Munk*
his ATTORNEY.

UNITED STATES PATENT OFFICE

LOUIS JUDELSON, OF NEW YORK, N. Y.

WINDING DRUM FOR WALL DRIERS

Original application filed July 8, 1927, Serial No. 204,248. Divided and this application filed May 14, 1929. Serial No. 363,061.

This invention relates to improvements in clothes driers of the wall type and has particular reference to a winding drum used to elevate and lower the drier and to hold the latter in any of its elevated positions.

This is a divisional application of my United States Letters Patent No. 1,731,050, issued October 8, 1929.

The invention has for its object to provide a winding drum of the character hereinafter fully described which is particularly applicable to the wall type of drier and which is simple in its construction, inexpensive to manufacture and sell, and efficient in operation.

I accomplish this object by means of the arrangement illustratively exemplified in the accompanying drawings, in which, Figure 1 is a side elevational view of the wall drier embodying in its construction my improved winding drum; Figure 2 is a substantially longitudinal sectional view of the drum and Figure 3 is a transverse sectional view taken on the lines 3—3 of Figure 2.

Referring to the drawings and particularly to Figure 1, 10 denotes an upright box shaped contrivance comprising a long narrow frame having a back board 11, side walls 12 and top piece 13, the front of the frame being open as is also the bottom end. The longitudinal upright side walls 12 are each provided adjacent their front ends with grooves or channels 14 which face each other across the front of the box and accommodate the opposite sides of a fixed operating board 15 at the lower end of the device and a sliding drier board or lift 16 throughout the length of the frame above the fixed board 15 and below the top piece 13. In order to insure perfect movement of the drier board 16 and adjacent the four corners thereof, rollers 17 are disposed on the upright sides, which rollers bear in the grooves and guide the lift during elevation thereof.

The lift 16 is manipulated by means of a block and tackle 18, one block being carried by the top piece 13, the other being linked to the upper end of the lift, while the cable 19 is threaded through both blocks 18 and projects throughout the length of the frame to a

pulley or drum 20, about which the cable is wound or unwound to alter the position of the lift, the other end of the cable 19 being brought over the second sheave of the block and attached about itself.

The drum 20, Figures 2 and 3 comprises preferably a flanged spool keyed to a rotary shaft 21 which is supported in a bearing 22 projecting through the mid portion of the fixed board 15 from face to face, as illustratively exemplified particularly in Figure 3. The bearing 22 is provided with a flange 23 disposed over and attached to the rear face of the fixed board 15 between the latter and the flange of the spool 20. The opposite end of the bearing 22 is flush with the front face of the fixed board 15 and the shaft 21 projects therebeyond to receive a toothed ratchet wheel 24 which is keyed to the shaft and provided with an integral collar 25. A housing 26 is disposed over the ratchet 24 and projecting radially and in an upward direction from the housing is an integral cone shaped portion 27 within which a pawl 28, in the form of a pin, is guided. The pin at its inner end in the housing is provided with a diametrically disposed block or toe 29 the length of which is greater than the diameter of the pin. The free end of the toe 29 is intended to enter the space between any adjacent teeth of the ratchet wheel 21 to lock the latter against rotary movement. The pin is normally urged in the direction of the ratchet wheel 21 by means of a spring, encircling the pin in the conical portion 27 of the housing and bearing at one end against the shoulders formed by the projecting portions of the toe 29 and at the other against the converging wall of the part 27. The outer end of the cone 27 terminates in a bearing 30 for the pin 28 and is provided with diametrically disposed grooves 31 and 32, one groove 31 being at right angles to the other groove 32 and cut to a substantially greater depth than that of the latter groove 32. These grooves are for the purpose of accommodating a pin 33 projecting transversely through the pawl or pin 28 at a point therein which, when supported in the deeper groove 31, permits the toe 29 to engage be-

tween the teeth of the ratchet wheel 24, and which when lifted with the pin 28 and turned to rest in the shallower groove 32 the toe 29 is free of the ratchet wheel and allows the 5 same to be rotated in one or the other direction.

Referring now to the drier proper, illustrated particularly in Figure 1, the board or lift 16 is provided with a bracket 38 projecting from the front thereof, the bracket having at its free end an upright pivot pin 39 about which a second bracket 40 is pivoted. The bracket 40 carries a triangularly shaped frame 41 which, in turn, supports by means 10 of a brace 43, another frame of the same shape and dimensions and tie bar 44'. The triangular frames 41 and 42 are arranged so that their base angles are uppermost and the apices are directed downwardly. At 15 spaced intervals throughout the length of the sides of the frames, are disposed drier bars or rods 44 upon which are hung the clothes to be dried. According to this arrangement, each row of bars 44 is disposed 20 inside the row immediately above, so as to enable all of the bars to support hanging articles without interfering with each other.

In operation, the drier is installed in a room by hanging it against a side wall or 30 by building it into the wall. The box 10 of course, is in upright position with the fixed board 15 at the lower end. A crank 45 is attached to the shaft 21 whereby the lift 16 may be lowered by manipulating the 35 pin or pawl 28 to disengage the ratchet wheel 24 and allow free rotary movement of the spool 20 to unwind the cable 19. It will be clear that because of the pivoted support for the drier frame, the same may be adjusted substantially 180 degrees to accommodate any condition of the room and wall space. After hanging the clothes upon the rods, 44, the crank 45 is manipulated to rewind the cable, resulting in the elevation of 40 the board 16 to any desirable height. The pin or pawl 28 is then turned to enable the 45 pin 33 to drop into the deep grooves 31 and the toe 29 between adjacent teeth of the ratchet wheel 21, thereby locking the same and holding the lift elevated.

Having now described my invention, what I claim and desire to secure by Letters Patent, is:

50 In a winding drum for a wall drier, the combination therewith of a ratchet wheel, a pawl guided radially of the wheel, a spring urging the pawl in the direction of the wheel and means for supporting the pawl out of 55 the path of the teeth of said wheel in one position and for allowing the pawl to engage the said teeth in another position, said means comprising a fixed housing for the pawl having a free end provided with cross cuts, 60 one cut being deeper than the other, and a

pin disposed transversely of the pawl to locate in one or the other of said cuts to assume its two operative positions.

In testimony whereof I affix my signature.

LOUIS JUDELSON. 70
